UNITED STATES PATENT OFFICE.

WILLIAM T. JOHNSTON, OF WASHINGTON, DISTRICT OF COLUMBIA, ASSIGNOR
TO BENJ. B. FRIEDENWALD, OF BALTIMORE, MARYLAND.

DESIGN FOR A BOTTLE-STOPPER.

SPECIFICATION forming part of Design No. 26,278, dated November 17, 1896.

Application filed September 23, 1896. Serial No. 606,791. Term of patent 14 years.

To all whom it may concern:

Be it known that I, WILLIAM T. JOHNSTON, a citizen of the United States, and a resident of Washington, in the District of Columbia, 5 have invented and produced a new and original Design for Disk Stoppers, of which the following is a specification, reference being had to the accompanying drawings, forming a part thereof.

10 In the drawings, Figure 1 is a plan view of the stopper. Fig. 2 is an edge view of the same, and Fig. 3 is a view of a modification.

15 The leading feature of my design consists in a disk having a projecting portion extending out from one peripheral edge of the stopper.

A represents the stopper, and B the projection from the edge thereof. The projection may be rectangular in shape, as shown in Fig. 1, or it may have the corners rounded, 20 as shown in Fig. 3.

What I claim is—

The design for a disk bottle-stopper substantially as herein shown and described.

In testimony whereof I affix my signature 25 in presence of two witnesses.

WILLIAM T. JOHNSTON.

Witnesses:

HENRY E. COOPER,
JAMES M. SPEAR.
